UNITED STATES PATENT OFFICE.

HORACE CHRISMAN, OF EDGEWOOD PARK, PENNSYLVANIA, ASSIGNOR TO PITTSBURGH METER COMPANY, OF EAST PITTSBURGH, PENNSYLVANIA, A CORPORATION OF PENNSYLVANIA.

DEVICE FOR SUPPORTING FLUID-CONTROL APPARATUS.

1,189,914.

Specification of Letters Patent.

Patented July 4, 1916.

Original application filed January 21, 1913, Serial No. 743,347. Divided and this application filed July 7, 1914. Serial No. 849,439.

To all whom it may concern:

Be it known that I, HORACE CHRISMAN, a citizen of the United States, residing at Edgewood Park, in the county of Allegheny 5 and State of Pennsylvania, have invented certain new and useful Improvements in Devices for Supporting Fluid-Control Apparatus, of which the following is a specification.

10 This invention is a division of my co-pending application, Serial No. 743,347, filed January 21, 1913, and relates to an improved device for removably supporting check valves and similar control apparatus 15 for controlling the flow of fluid through conduits, etc.; and it has for its primary object the provision of an improved supporting means which is detachably mounted so that it can be readily removed together with 20 the fluid control device.

The foregoing, together with such other objects as may hereinafter appear or are incident to my invention, I obtain by means 25 of a construction illustrated in preferred form in the accompanying drawings wherein I have shown my improvement applied to a metering device.

Of the drawings, Figure 1 is a longitudinal section through a casing in which my invention is embodied; Fig. 2 is a similar section with the parts shown in a different position; and Fig. 3 is a plan view of Fig. 1 with the top plate and the positive, or normal flow meter, removed.

35 Referring to the drawings, 3 is a casing in which the fluid control device is mounted. The casing is provided with an inlet opening 4 and an outlet opening 5, the casing being placed in the main (not shown) so that 40 the ports are in the line of flow through the main. Adjacent to the inlet opening, the casing 3 is provided with a seat 6^a on which a sleeve 6 is mounted, said sleeve being detachably held in position by means of screws 45 6^b or other suitable means. The upper part of the casing is enlarged to form a chamber C, this chamber being closed by means of a removable cover plate 3^a. The sleeve 6, at its inner end, is provided with a sloping 50 valve seat 7 against which the disk 7^a of the swinging flow control device A (which in the present showing is a normal flow meter) is adapted to take. The disk 7^a is pivotally

mounted on the brackets 8 formed on the upper portion of the sleeve 6, and the normal flow meter is of the same construction as that shown in the aforesaid co-pending application. For the purposes of this application, it will be sufficient to state that under all normal flows through the main, 55 the valve disk 7^a is normally gravity-held on its seat 7, and that when in this position, the valve 16 controlling the inlet passage 12 leading to the normal flow meter is held in open position so that the flow takes place 60 through the normal flow meter. When there is a heavy draft—as that, for example, which takes place in cases of fire—the valve disk 7^a is unseated and assumes the position indicated in Fig. 2, the normal flow meter 70 then lying in the chamber C of the casing 3. The valve disk 16 automatically closes when the disk is unseated, and no flow takes place through the normal flow meter. In cases of back pressure, the disk 7^a acts as a check 75 valve.

For measuring abnormal or heavy flows, I have provided a proportional flow meter B which is mounted in the apertured portion 9 formed in the upper part of the sleeve 80 6, said proportional flow meter being detachably fastened in any preferred manner to the flanges 10. The proportional flow meter communicates with a port 30 which is formed in the casing 6, and which opens in 85 the face of the valve seat 7 in position to be covered by the valve disk 7^a. A tongue or nose 33 is detachably secured to the valve disk 7^a and normally lies in the port 30, said nose being tapered so as to automatically 90 proportion the opening of the port 30 to the main opening which is formed when the valve disk 7^a unseats.

The indicators for the normal flow and proportional flow meters, respectively numbered 20 and 31, are arranged on the exterior of the casing 3, said indicators being operated by any preferred form of actuating means D and E connected to the meters. When it is desired to remove, inspect, repair 95 or replace the fluid control devices, the only steps necessary are to remove the cap or cover plate 3^a, disconnect the actuating means D and E, and take out the screws 6^b; and when this has been done, the sleeve 6 100 and all of the parts that it carries can be

removed intact. It will also be seen that this arrangement makes it possible to assemble all the parts and insert them bodily in the casing. The construction is also such 5 that if desired, either the normal flow meter or the proportional flow meter can be removed independently of one another. In case it is desired to detach the normal flow meter, the plates 21 are removed; and in 10 case it is desired to detach the proportional flow meter, the screws 29^a are removed.

It will be clear that the arrangement is applicable to a variety of different forms 15 of fluid control apparatus, and I do not intend to limit the invention to the application to metering devices which are shown in the drawings.

A particular advantage incident to my invention resides in the fact that the sleeve 20 offers no obstruction to the passage of fluid, while at the same time ready detachment is possible.

I claim:—

1. In a device of the character described 25 the combination of a casing provided with a seat, a sleeve resting in said seat, said sleeve having an attaching flange and being

provided with a fluid control device adapted to control the flow therethrough, and fastening screws passing through said flange 30 and into the casing, whereby the sleeve and the fluid control device may be bodily removed from said casing.

2. In a device of the character described the combination of an open-ended casing 35 having a seat adjacent to one opening, a sleeve resting on said seat and provided with a fluid control device, and means for detachably securing the sleeve in position, said casing being provided with a detachable 40 cover for the withdrawal of the sleeve together with its fluid control device, there being substantially no obstruction in the chamber of the casing between the sleeve and the cover whereby the sleeve may be 45 lifted substantially directly out of the casing.

In testimony whereof I have hereunto signed my name in the presence of the two subscribed witnesses.

HORACE CHRISMAN.
